H. E. BRYANT

OVERRUNNING PREVENTER FOR WINDING MACHINES

Filed Sept. 16, 1925

UNITED STATES PATENT OFFICE.

HENRY E. BRYANT, OF PROVIDENCE, RHODE ISLAND, ASSIGNOR TO TUBULAR WOVEN FABRIC COMPANY, OF PAWTUCKET, RHODE ISLAND, A CORPORATION OF RHODE ISLAND.

OVERRUNNING PREVENTER FOR WINDING MACHINES.

Application filed September 16, 1925. Serial No. 56,703.

To all whom it may concern:

Be it known that I, HENRY E. BRYANT, a citizen of the United States, residing at Providence, in the county of Providence and State of Rhode Island, have invented new and useful Improvements in Overrunning Preventers for Winding Machines, of which the following is a specification.

The present invention relates to machines for winding filamentous or strip material by the action of a rotating winding head carrying a supply of such material on an independently rotatable spool or the like. Its object is to prevent continued rotation of the spool after the winding head has been abruptly stopped or quickly retarded. For instance, assuming that the winding head is normally rotated at high speed, and that the machine is equipped with a brake or other stop motion device for quickly arresting the motion of the head when some untoward accident occurs, such as breaking of the stock being wound or its failure to be fed properly to the winding point, then it is desirable to stop the rotation of the stock holding spool or reel also as soon as possible in order to prevent unwinding and snarling of the stock supply, or other danger liable to result from continued free rotation of the supply spool.

I have accomplished this object by providing in connection with the winding head and supply spool, in a machine of the character above indicated, an automatic stop or clutch device which is inoperative so long as the winding head continues to operate in its normal manner, and becomes operative instantly to arrest the spool when the winding head is itself arrested. The embodiment of the invention herein illustrated has been designed for use with a machine for winding strip material into tubular form, and particularly for making flexible metallic conduit or armor for electrical conductors; such a machine being disclosed in my pending application filed February 17, 1925, Serial No. 9,782. The drawings provided with this specification illustrate so much of the said machine as is sufficient for explanation of the principles of the invention and the construction of the specific embodiment herein referred to. It is to be understood, however, that the invention is not limited to use with that specific machine, but is applicable also

to other machines which include a rotating winding head, an independently rotatable spool or equivalent stock holder, and means for stopping the winding head.

In the drawings:

Figure 1 is a side elevation, with parts broken away and shown in section, of the winding machine adapted to wind armor upon cable and having one embodiment of the present invention applied thereto;

Fig. 2 is an end elevation of the machine showing on an enlarged scale a fragment of the winding head and a fragment of the stock holding spool, together with an automatic stop mechanism for arresting the winding head and means embodying the invention for arresting the supply spool at the same time;

Fig. 3 is a fragmentary view illustrating the manner in which the stopping mechanism acts to arrest the winding head and the spool;

Fig. 4 is a fragmentary sectional view illustrating one means for making a flexible connection between the stop motion trip and the spool arrester which form parts of the above mentioned mechanism.

Like reference characters represent the same parts wherever they occur in all the figures.

The part of the machine which I have called the "winding head" is that designated by the numeral 21 in the drawings. It is secured on one end of a shaft 22 which rotates in bearings 23 and 24 on a base or frame 25. Such head may be driven by any suitable means, such as a motor 26 mounted on the frame 25 and having a shaft which is coupled with the shaft 22 by a belt or chain 27 and complementary pulleys or sprocket wheels.

The winding head is cylindrical in form, having an end wall 29 and an outer side wall 30. It also has an interior cylindrical bearing surface 31, the said outer wall and bearing being coaxial with the shaft 22. In the annular space between the bearing 31 and the wall 30 is a spool holding the stock 32 and having a hub 33 surrounding and rotatable upon the bearing surface 31, and a flange or base 34 bearing against the end wall 29 or against roller bearings mounted in said end wall. The stock is drawn from the spool and carried around a guide roll

35, mounted on the head, and led thence to the winding point. The head is also equipped with stock feeding, forming and laying devices, for a full disclosure of which reference may be had to the aforesaid application; but as such disclosure is not essential to an explanation of the present invention, it is not repeated herein. The requirements of the present disclosure are met by 10 the explanation that the winding head is rotatable and that the stock-holding spool is carried by the head and is independently rotatable relatively thereto about the same axis.

15 The stock shown illustratively herein is a metallic strip or ribbon wound in the form of a coil and mounted on the spool, surrounding the hub 33 thereof and bearing against the face or flange 34. Such showing, however, is illustrative and typical rather than exclusive. The term "spool" which I have used herein is a generic term intended to include any device similar or equivalent to the so-called spool herein illustrated and adapted to hold a supply of stock in coil form.

When the winding head is rotated to form the stock into the article of manufacture which is the final product of the machine, 20 the spool is rotated also in the same absolute direction, meaning by "absolute direction" the direction with respect to the stationary parts of the machine and other objects, but at a different speed, the speed differential 25 being due to the delivery of stock from the spool to supply the demands of the manufactured article or goods. Thus the spool rotates relatively to the winding head and the direction of such relative rotation may 30 be the same as, or opposite to, the direction in which the stock is wound to form the coil carried by the spool. The rotation of the head is much more rapid than the relative rotation of the spool, hence when the head 35 is suddenly stopped the spool tends to continue on in the direction of its absolute rotation whether the relative rotation is in the same, or the opposite direction. Such continued rotation or overrunning of the spool 40 is liable to have more or less objectionable and serious results, well understood by those acquainted with the art. The object and accomplishment of the invention is to prevent such overrunning; and the embodiment 45 of the invention disclosed in this specification is adapted to prevent such overrunning in either direction, that is whether the relative rotation of the spool is in the same direction or opposite to the rotation of the 50 head.

I will now briefly describe the stop motion mechanism, in connection with which I have applied the present illustrative embodiment of the invention, such stop motion mechanism being substantially the same as the one

disclosed in my prior application herein identified.

The guide roll 35 previously mentioned controls a brake for stopping the winding head in case either the stock should break 70 or fail to pass freely enough to the winding point. Said roll is mounted upon an arm 36 connected to a rock shaft 37, and engaged by a pin and slot connection 38 with an arm 39 on a rock shaft 40. These shafts and the 75 arm 39 are acted upon by springs tending to throw the parts just described from the normal position, which is that shown in Figure 2, to the position shown in Figure 3, and also resisting movement of the guide roll under the pull of the stock toward the axis of the head. A double cam 41 is mounted on the shaft 37 and bears on an arm 42. Said arm 42 is connected to a rock shaft 43, mounted in a bearing secured to the outer 80 wall of the winding head, and to the rock shaft is secured a second arm 44 having a finger 45, which I call a "trip finger," extending through a hole in said outer wall. A spring 46 normally retracts the finger and 85 holds arm 42 against the cam 41.

Beside the outer surface of the wall 30 there is arranged a brake member 47 having a friction face complementary to the wall 30 and arranged to slide in a stationary guideway, which guideway is so arranged that the brake member may be moved clear of the head or brought into frictional engagement with it. A spring 48 tends to move the 90 brake into contact with the head, but such movement is normally prevented by a latch 49 interlocked with a projection 50 on the brake, and having a trigger arm 51 which extends near to the circumference of the head and in the same zone with the path in 95 which the trip finger 45 travels. Normally the trip finger passes clear of the trigger arm, but when the arm 36 is thrown outward, as shown in Figure 3, in consequence of breakage of the stock, or if it is drawn inward by excessive tension of the stock, the trip finger is projected, by turning movement of the double cam 41 in one direction or the other far enough to engage the trigger 100 arm 51 and release the latch, thereby permitting 105 the brake to be set.

There is connected to the arm 42, in a flexible manner, a hook or pawl 52, or equivalent clutch member, which is located beside the rim of the spool flange 34, and is adapted to enter any one of a series of notches 53 in said rim, but is withdrawn therefrom by the action of spring 46, at all times except when the trip finger is projected as last 110 above described. That is, the same movement of the cam 41 which projects the trip finger also brings the hook or pawl 52 into engagement with the rim of the spool. The yielding connection between said pawl and the arm 42 allows the pawl to rest against 115 the rim of the spool flange 34.

such rim if no notch happens to be in register with the pawl when the latter is thus moved, and causes it to enter the next notch which comes in registry with it in the relative rotation of the spool thereafter occurring.

A suitable means for connecting the arm 42 and pawl 52 together in a yielding and elastic manner is shown in the drawings, and 10 more particularly in detail in Figure 4. A coupling pin 54 is passed loosely through registering holes in the overlapping ends of the arm and pawl, such pin having greater length than the combined thickness of these 15 overlapping ends and having heads on its ends. A spring 55 is confined between one of said heads and the adjacent one of the overlapping members, in this case the arm 42. In order to prevent rotation of the pawl 20 about the coupling pin, a second pin 56 is set into the arm 42 and projects through a slot or notch in the adjacent part of the pawl. This second pin or steady pin as it may be called, while it prevents the pawl 25 from turning on the arm 42 out of the plane of the spool flange, does not interfere with the free movement of the pawl in such plane, permitted and caused by the loose and resilient mounting of the connecting pin 54, 30 within the small range of movement necessary for making engagement with the spool in the manner above pointed out.

It will be seen that the member 52 thus named as a pawl is in effect a clutch adapted 35 and operative to couple the spool to the head by engagement with one or another of the notches 53 in the manner to prevent positively any relative rotation of the spool in either direction. It is within my contemplation and the scope of the protection 40 which I claim, however, to make the clutch positive in one direction only, and otherwise to vary the form of the clutch pawl and of the complementary notches and teeth, or abutments, in the spool, in any manner desired. 45 Of course if the clutch is made positive in one way only, it will be then constructed and arranged to oppose movement of the spool in the direction in which its absolute rotation 50 takes place.

It will be appreciated that the clutch here shown is operated directly by the same means which controls the stop motion mechanism; and that it may become effective to 55 couple the spool to the winding head even before the stop motion mechanism has acted to arrest the head, and will do so if one of the notches in the spool happens to lie beside the pawl at the instant when the stop 60 controller acts; while in other conditions it will do so more or less quickly depending on the closeness of the spacing of the notches. Thus, when the stop motion mechanism is put into action, the spool is brought 65 to rest simultaneously with the winding

head, and the latitude left for overrunning of the spool is limited to the distance between two of the notches 53, which distance may be so short as to make the overrunning of the spool altogether negligible. 70

The brake may be set also when it is desired to stop the machine for any reason at any time, even though no accident has occurred such as would cause its automatic stoppage. Such voluntary stoppage may 75 be effected by manually releasing the latch 49 and so causing the brake 47 to be set, or by applying another brake with which the machine may be equipped in practice. Stopping of the machine in this manner immediately causes the clutch to operate and prevent overrunning of the spool; for if the overrunning rotation of the spool is in such direction as to wind up the stock on the 80 spool, the displacement of the guide by the pull of the stock couples the clutch, or if the spool runs with tendency to unwind the stock from it, the slackening of the stock allows the spring to operate and throw the guide outward, also setting the clutch. 85 This overrunning preventer therefore automatically prevents the momentum of the spool from either stretching and breaking the stock, or from unwinding and allowing the stock to snarl when the machine is 90 intentionally stopped. It makes no difference whether the coil of material on the spool is wound so as to cause relative movement of the spool in the same direction as its absolute rotation, or in the opposite direction; 100 in either case the clutch is set and overrunning of the spool prevented, automatically, in consequence of manual stoppage of the machine. 95

In addition to the clutch means herein 105 described, the machine may be equipped with frictional traction means, such for instance as that shown in my prior application Serial No. 9782, for causing rotation of the spool with the head when the machine 110 is started up and for maintaining sufficient tension in the stock while the machine continues in normal operation.

It is to be understood that the invention 115 is not limited to the combination of the overrunning prevention means with a stop motion mechanism of the particular kind and construction herein shown, and that said mechanism is simply illustrative of an operative stop motion device with which the invention may be used, and typifies any such device, whether of the same character or of specifically different character with which the invention may be used. 120

The overrunning prevention device here 125 shown is one of several devices for the same purpose which I have invented, others of such devices being disclosed in patent applications filed concurrently herewith. One of its distinguishing characteristics with refer-

ence to the embodiments of the same generic invention disclosed in said other applications is that it is primarily controlled and made operative by the stop motion controller, which in turn is directly controlled by the stock being operated on, whereas in said other embodiments the arrest of the spool is effected by a slackening of the speed of the winding head to such an extent that the relative motion of the spool is reversed. Another distinguishing characteristic is that it is, or may be, positive in both directions. So far as the device shown in this and the above mentioned concurrently filed applications embody a common invention, such invention is claimed generically herein, together with claims for the species here shown.

Having thus described the principles and one specific embodiment of the invention, although without attempting to describe all possible forms of the invention or all of its modes of use, I declare that what I claim and desire to secure by Letters Patent is:

1. In a winding machine a rotatable winding head, a rotatably mounted spool carrying the material to be wound, a guide for leading said material from the spool to the winding point, said guide being supported

by the head and movable in opposite directions from a normal position when the machine is in operation, a stop mechanism adapted to arrest said head, a normally inoperative clutch for coupling the spool to the head, and means operated by abnormal movement of the guide in either direction from its normal position for setting said clutch to thus couple the head and spool together.

2. In a winding machine a rotatable winding head, a rotatable supply spool coaxial with said head, a guide for the material being wound in its course from the spool to the winding head, said guide being movably

mounted on the head, a spring arranged to exert force on said guide in opposition to the force applied thereto by the tension of said material, and means operated by the guide following movement of the latter under the unopposed force of said spring for coupling the spool to the head.

3. In a winding machine a rotatable winding head, a rotatably mounted spool carrying the material to be wound, a guide for material to be wound arranged to deflect such material in its course from the spool to the winding point, said guide being mounted with ability to move in the direction of the pull imposed by said material and in the opposite direction as well, a spring arranged to exert force on said guide in opposition to the pull of said material, the guide being movable under the unopposed force of the spring away from its position of equilibrium

when acted on at the same time by the spring

and the material, and a clutch for preventing overrunning of the spool operable for that purpose by the guide when the latter is moved under the unopposed force of the spring.

4. In a winding machine a rotatable winding head, a spool mounted on said head with provision for independent rotation, a positive clutch means adapted to lock said head and spool together in a positive manner and prevent any relative movement between them, means normally holding said clutching means in an inoperative non-locking position, stopping means for arresting said head, and means for placing said clutch in locking position simultaneously with actuation of said stopping means.

5. In a winding machine a rotatable winding head, a spool mounted on said head with provision for independent rotation, a positive clutch means adapted to lock said head and spool together in a positive manner and prevent any relative movement between them, means normally holding said clutching means in an inoperative non-locking position, and common means controlled by the material being wound for stopping the head and at the same time putting said clutching means into locking condition.

6. A machine for winding material comprising a rotatable winding head, a supply spool for the material being wound, said spool mounted on the head and being rotatable relatively thereto, a normally inoperative stop mechanism for arresting the head, a trip device in place thereof, mechanical means normally restrained by the material being wound for putting said stop mechanism into operation independently of centrifugal force, when the restraint of the material is relaxed, and a clutch connected with said trip device for coupling the spool to the head at the same time.

7. In a winding machine a rotatable winding head, an independently rotatable supply spool, a normally inoperative means for stopping the rotation of said head, a trip member carried by the head for causing operation of said stopping means under control of the material being wound, and a positive clutch member carried by said trip member for coupling the spool and head together when said trip member effects operation of the stopping means.

8. In a winding machine a rotatable winding head, a spool rotatable relatively to the head and having clutch abutments, a stop motion trip member mounted on the head, and a positive clutch member carried by said trip member and having a portion movable into engagement with one of said abutments.

9. In a winding machine a rotatable winding means, an independently rotatable spool for holding the material to be wound, a guide around which said strip material is

caused to pass on its way to the winding point, a pivoted arm by which said guide is carried, a spring tending to move said arm oppositely to the direction of force application thereon by the material, a cam connected to said arm and movable thereby, and an overrunning preventer for said spool operable by said cam to arrest the spool.

10. In a winding machine, rotatable winding means, a supply spool rotatable with and independently of said winding means, a normally inoperative clutch adapted to be connected with said spool to prevent such independent rotation thereof, a rock shaft, a 15 cam mounted on said rock shaft adapted to displace said clutch into its spool coupling position, an arm secured to said rock shaft having a guide for the material to be wound arranged to deflect such material in its 20 course from the spool to the winding point, and a spring acting on said arm in opposition to the force applied to the arm by said material, the arm and cam being movable by the unopposed force of said spring into 25 the position for causing coupling of the clutch.

11. In a winding machine a rotatable winding apparatus, an independently rotatable supply spool, a brake for stopping the 30 rotation of said apparatus, a normally inop-

erative clutch for coupling the spool to the winding apparatus to prevent independent rotation of the spool, and means for causing coupling of said clutch when the winding apparatus is arrested.

12. In a winding machine a rotatable winding apparatus, an independently rotatable supply spool, a brake for stopping the rotation of said apparatus, a normally inoperative clutch for coupling the spool to the 40 winding apparatus to prevent independent rotation of the spool, a guide for the material to be wound arranged to deflect such material from a straight line in its passage from the spool to the winding point, a 45 spring acting on said guide in opposition to the force applied to the guide by said material, said guide being movable against the force of the spring by abnormal increase in the tension of the material, and movable in 50 the opposite direction by the spring with abnormally slackening of the material, and means operable by said guide in its abnormal movement in either direction for coupling the clutch to prevent independent movement 55 of the spool.

In testimony whereof I have affixed my signature.

HENRY E. BRYANT.
